United States Patent Office

Des. 196,311
Patented Sept. 17, 1963

196,311

PLATE OR SIMILAR ARTICLE

Shigeru Masuda, Nagoya, Aichi, Japan, assignor to Noritake Co., Inc., New York, N.Y., a corporation of New York

Filed July 30, 1962, Ser. No. 71,100

Term of patent 7 years

(Cl. D44—15)

The FIGURE is a plan view of a plate or similar article, showing my new design.

The plate is of a conventional configuration when viewed from the side and bottom thereof.

I claim:

The ornamental design for a plate or similar article, substantially as shown and described.
